UNITED STATES PATENT OFFICE

HARRY G. LANGE, OF ST. ELMO, ILLINOIS

PORTABLE BUILDING

Application filed October 12, 1929. Serial No. 399,258.

This invention relates to portable building structures and has more particular reference to a sectional house of octagonal configuration constructed from ready-cut and ready-built portable sections.

My principal aim is to generally improve upon structures of this class by providing an arrangement which is characterized by especially designed ready made sections of a form which facilitates assembling, and expedites handling in packing, storing, and handling from the factory to the ground on which the house is to be erected.

The particular features, advantages and diversified uses of this improved construction will become more readily apparent from the following description and drawings.

One structural improvement is predicated upon the provision of a novel roof structure made from substantially triangular companion sections which, when assembled, form a substantially truncated pyramidal roof, said roof being advantageous in that it is made to accommodate a ventilator.

Another feature in the construction is the two-part floor composed of substantially semi-octagonal complemental sections. A further feature is found in the employment of substantially rectangular side panels properly braced and provided with dowel pin connectors to facilitate handy erection and assembly.

A still further feature is embodied in practical attaching cleats carried by the upper portion of the side panels and joined to adjacent rafters of the roof section.

Other features in the construction will become more readily apparent from the following description and drawings:

In the drawings:

Figure 1 is an elevational view of an octagonal house constructed in accordance with the present invention.

Figure 2 is a top plan view of the same.

Figure 3 is a central vertical section taken approximately on the plane of the line 3-3 of Figure 2.

Figure 4 is a horizontal section on the line 4-4 of Figure 3.

Figures 5 and 6 are detail cross sections on

the lines 5-5 and 6-6 respectively of Figure 2.

Figure 7 is a fragmentary perspective view showing one of the dowel pin connectors.

As before stated, the building is octagonal in outline and configuration. Starting then with the floor, it will be observed that it is composed of a pair of duplicate half sections 8 and 9 which are disposed in abutting relationship. These comprise floor boards 10 fastened to appropriately arranged floor joists 11.

Around the margin and projecting to the exterior is a ledge 12 which functions as a water apron as well as a supporting ledge. The adjacent joists, that is the two central joists of the sections 8 and 9 are bolted together as at 13.

The sectional side walls or panels are generally designated by the reference characters 14 and each one comprises a plurality of abutting vertical boards 15 joined together in assembled relation by a plurality of horizontally disposed vertically spaced braces. These braces, because of their functional results are separately distinguished in the following manner.

The lowermost brace 16 is spaced upwardly from the lower edges of the board 15 and functions as a rest in that it rests upon the marginal portion of the floor. In addition, it constitutes a mop board. This allows the projecting lower end portion of the boards 15 to seat firmly on the ledge 12 as shown in the assembly of Figure 3.

The intermediate or central brace 17 may well be distinguished as a rail. The top braces which terminate flush with the upper ends of the boards 15, may be defined as roof supporting and attaching bars 18. All of these braces 16, 17 and 18 are provided with alternate socket and dowel pins. The dowel pins are each designated by the reference character 19 and fit into companion sockets in the complemental ends of the adjacent braces. This affords an expeditious method of firmly attaching the side panels in joined relationship.

In this connection, I call attention to the fact that the reference character 20 in Figure 100

6 designates one of a plurality of metal attaching and coupling cleats. The vertical portion 21 is fastened firmly to the bar 18. The upper end portion is directed laterally outward and projects above the bar.

5 The laterally directed upper end portion of each cleat is distinguished by the reference character 22.

10 I now call attention to the construction of the roof. It will be observed that this is of truncated pyramidal configuration and is composed of a plurality of separate and independent sections denoted by the reference characters 23. Each section is substantially 15 triangular in plan view. It comprises a plurality of boards suitably attached to the rafters.

20 In each section we find three rafters, namely the longitudinal outwardly diverging rafters 24, joined at their outer ends to a relatively short transverse rafter 25. The latter rafter is spaced inwardly from the outer ends of the rafters 24 as clearly shown in Figure 6 so that it rests in an inclined position 25 on the upper edge portions of the side panels 14. This places it in a position to permit the upper end 22 of the cleat 20 to be nailed, screwed, or otherwise fastened firmly thereto.

30 It will be observed after examining Figure 5 that the adjacent longitudinal rafters are secured together by bolts 25. Moreover, the crown portion of the abutting edges of the respective roof sections 23 are covered 35 by suitable cap forming strips 26. This provides a weatherproof roof.

40 The ventilating features comprising hingedly mounted windows 27 carried by certain of the side panels together with a roof ventilator generally indicated at 28. This ventilator comprises a neck 29 which fits into the roof opening at the apex portion of the roof. In addition, there is a collar forming 45 flange 30 and an external water shedding hood 31. This is shown plainly in Fig. 3.

45 I might mention also the provision of a suitable door 32 forming an appropriate entrance.

50 This octagonal house or cottage is a unique practical idea in portable structures, adaptable to scores of uses. Every business or individual who has need for a small portable structure will find a cottage of this type ideal in every respect; and for a great many uses, it will prove economical to erect a number of them instead of a larger, permanent building.

55 It functions as a spacious one-roof cottage and the interior is ample to accommodate a complete room of furnishings. The desirable features of ventilating add to the comfort of the occupants. There are many other commercial features and advantages which will be evident to those skilled in the art to which the invention relates. Likewise it is thought that by considering the de-

scription in connection with the drawings, the structural features will be quite plain.

Minor changes in shape, size, materials and rearrangement of details coming within the field of invention claimed may be resorted to 70 in actual practice if desired.

I claim:

1. The portable building comprising an octagonal floor consisting of a pair of symmetrical half sections disposed in abutting relation, a marginal ledge at the peripheral portion of the floor and projecting outwardly therefrom in a plane below the floor surface, a plurality of separable side walls attached to and rising perpendicularly from said floor to 80 form an octagonal enclosure, and a sectional roof mounted on said side walls, said side walls being provided on their inner faces and adjacent the lower ends with mop boards engaged over the outer edge portions of the 85 floor sections and supporting the side walls with their lower ends seated upon the said ledge.

2. A portable building structure comprising a wall composed of separable panels of 90 rectangular configuration arranged to form an octagonal enclosure of uniform diameter, each of said panels being provided on its inner face and adjacent its upper end with a roof supporting bar, a conical roof structure 95 formed of a plurality of triangular roof panels respectively provided on their inner faces with longitudinal side rafters converging at their inner ends and transverse base rafters between the divergent outer ends of 100 the side rafters and spaced inwardly from the outer end of the roof panels to rest upon the said supporting bar of a subjacent wall panel, and connecting straps between the supporting bar of a wall panel and the base 105 rafter of the roof panel supported thereon.

3. A portable building comprising a perpendicular enclosing wall formed of a series 110 of separably connected rectangular sections including a door bearing section, one or more window bearing sections, and solid sections relatively disposed in side to side abutment to form an octagonal enclosure, a roof composed of a series of separably connected triangular sections corresponding in number 115 to the number of rectangular wall sections and arranged above the latter so that each triangular roof section is supported adjacent its base on the upper end of a corresponding wall section so as to extend inwardly and upwardly therefrom to form in conjunction with the other triangular sections a conical roof, angle brackets connecting the base of each roof section with the supporting end of the corresponding wall section for supporting the roof section angularly inclined above 120 the wall, and a flooring for said enclosure.

In testimony whereof I affix my signature.

HARRY G. LANGE.
